UNITED STATES PATENT OFFICE.

GEORGE W. LANCASTER, OF RICHMOND, VIRGINIA.

SHEET-METAL WINDOW AND BALANCING SHEET-METAL SASHES.

Application filed April 14, 1924, Serial No. 706,392. Renewed March 26, 1927.

In a sheet metal window including balancing sashes of a sheet metal design, the invention has for its purpose the provision of a structure wherein the parts are simpler, 5 more condensed and compact and more easily operated than the structure disclosed in application for patent on a similar device filed April 11, 1923, Serial No. 631,416, in the name of George W. Lancaster.

10 In the application above identified, certain of the sashes counterbalance and others are weight-balanced and the sashes are mounted between outstanding guides.

The idea of mounting the sashes between 15 outstanding guides causes the stiles of the window frame or casement to be constructed of considerable depth and the weights are mounted in guides of the stiles forwardly of the sashes.

20 This character of construction provides considerable unused space on the interior of the stiles.

Furthermore, by mounting the several sashes between outstanding guides of the 25 stiles, the balancing chains on the sashes are more or less exposed and should the sashes be raised quickly, the chains are very liable to loop or move outwardly from between the guides and hence cause considerable inconvenience and delay in operating the sashes.

Also, in the above identified application, main and auxiliary lintels are employed for the purpose of housing and obscuring the pulley supports or brackets.

35 Additionally, the sashes in said application have mitered top, bottom and side rails and, while such joints can be made to insure a neat finish, the cost of production and installation of such sashes, in some instances, 40 is somewhat prohibitive.

The above features have been the means of necessitating the provision of a structure considerably simplified and cheapened, the aim being to eliminate such features.

45 For example, another purpose is to provide, in a casement or frame, stiles provided with guides for the sashes and the weights, and also guides for balancing chains and the extensions of the sashes, thereby utilizing 50 the unused space mentioned as existing in said application, above identified.

It will be noted in the present case that 55 the guides for the sashes are countersunk and do not receive the full thicknesses of the sashes, hence, due to the countersinking of the guides, the heretofore mentioned un-

used space is substantially occupied by the sash guides as well as the chain guides.

A still further purpose is the provision of guards extending within the chain guides, 60 thereby eliminating the possibility of the balancing chains looping or moving outwardly of their guides, which has been found to be an objectionable feature to a degree.

A further purpose is to provide, in a window casement or frame, stiles wherein the weight guides are to the side of the chain guides, portions of the latter acting materially in guiding the weights during their movements, especially the weights which balance the upper outermost sash.

A still further purpose is the provision of a structure wherein the actuating members of the weights (which counterbalance the upper outermost sash) project inwardly of the 75 room instead of laterally of the stiles in a direction parallel with the sashes, thereby rendering them more easily grasped for actuating the weights and thereby securing a more positive movement of the weights and enabling the weights to be unlatched considerably easier.

In general, the present construction of sheet metal window, together with its balancing sheet metal sashes, is more practical, 80 more condensed and compact in structure, and has been found to fulfill the commercial demands at a considerably less cost.

Still further, the invention aims to eliminate the above mentioned mitered joints in 90 the construction of the sashes and at the same time provide a simpler assembly of the top, bottom and side rails thereof, in fact, a more rigid assembly.

Furthermore, the sashes in the present case 95 are much thinner, less material being used, and by far is a cheaper construction.

Also, the present invention aims to provide a novel construction for connecting the top, bottom and side rails of the sashes and, 100 due to the balancing chains being connected to the sashes by rivets or the like, the joints of said rails are more rigid.

Instead of constructing sashes with their entire thicknesses engaged between outstanding guides, as in the aforesaid application, the present sashes are thinner and have reduced extension flanges on their side rails which engage within the countersunk guides of the stiles, said flanges providing much 105 better means to which the balancing chains may be connected. It will be noted that

throughout substantially the entire construction, the various joints of the sheet metal of the frame or casement and the sashes are spot-welded.

- 5 The present invention also aims to eliminate, in the construction of the head of the casement or window frame, the auxiliary lintel, and since the brackets or holders for the pulleys are engaged with the depressed 70
10 seats or channels of the stiles, the pulleys are located in positions to be engaged by the balancing chains, thereby facilitating the 75
15 operation of the sashes with minimum binding thereof as well as the chains.
- 15 It is to be understood that the particulars herein given are in no way limitative and that, while still keeping within the scope of the invention, any desired modifications of detail and desired proportions may be made 80
20 in the apparatus according to the circumstances.

The invention comprises further features and combinations of parts to be hereinafter set forth, shown in the drawings and 85
25 claimed.

In the drawings:

Figure 1 is a view in perspective of the improved sheet metal window and balancing sheet metal sashes constructed in accordance 90
30 with the invention.

Figure 2 is a vertical sectional view on line 2—2 of Figure 1, showing the relativity of the various sashes and their balancing means.

35 Figure 3 is a horizontal sectional view on line 3—3 of Figure 2.

Figure 4 is a horizontal sectional view on line 4—4 of Figure 2, taken through the head of the casement or frame.

40 Figure 5 is an enlarged detail perspective view of the bracket or casing which supports the pulleys for the balancing chains.

Figure 6 is a perspective view of the pulley bracket, looking upwardly thereunder.

45 Figure 7 is a detail perspective view of the weight which counterbalances the upper outermost sash.

Figure 8 is a sectional view on line 8—8 of Figure 5.

50 Figure 9 is a sectional view on line 9—9 of Figure 5.

Figure 10 discloses bracketed detail perspective views of portions of the head rail of the casement and one of the stiles.

55 Figure 11 is a detail perspective view of a part of one of the stiles, and showing the chain guides and chain guards.

Figure 12 is a detail perspective view of one end of one of the sashes.

60 Figure 13 discloses detail perspective views of the disconnected ends of the top and one side rail of one of the sashes.

Figure 14 is a detail perspective view of one end of the bottom rail of one of the sashes.

Referring to the drawings, 1 designates the window frame or casement as a whole which comprises the sheet metal sill 2, the stiles 3 and the lintel or head 4 which are hollow and are secured together in any suitable manner, preferably by spot-welding. Any suitable sheet metal may be used in this structure, galvanized, oxidized, or otherwise finished. Obviously, brass, aluminum, or like metal may be used.

75 It will be noted that the sill at its ends may be cut away, as shown at 5, to conform to the angular contour of the adjacent surfaces of the stiles.

80 Referring to Figure 10, it will be seen that the lintel or head is shaped or cut away at its end, as shown at 6, to conform to and engage the contour of the stile at its upper end.

85 The two stiles are correspondingly constructed and are provided with depressed channels 7 which not only act as guides for weights 8 but also contain the sheet metal guides 9 which receive weights 10. The guides 9 are substantially half the width of 90
90 the depressed channel 7 and are spot-welded in position, as shown clearly in Figures 3 and 4.

95 The inner wall 11 of each guide 9 terminates in a flange 12 which is rebent as shown and assists in guiding the weight 10. The opposite portion of each guide 9, that is, the portion nearest the front of the stile, is bent to provide the lateral part 13 which is rebent at right angles to provide the guide flange 14 which overlies the weight 10 and cooperates with the body of the guide 9 to properly 100
100 guide the weight 10 during its movement.

105 The outer portion of each stile is of greater thickness than the inner portion, hence its wall 15 constitutes a guide for additionally guiding the weight 8.

110 Adjacent the depressed channels are guides 16 for the sashes and guides 17 for the sash chains. These guides consist of the angular rails 18, the channel rails 19, the outer angular rails 20 and the plates 21. It will be noted that the plates 21 contain the depressed channels or guides 17 which not only receive the sash chains but also receive 115
115 extension guide flanges 23 of the upper outermost and the lower innermost and the intermediate sashes 24, 25, and 26 and 27.

120 Portions of the angle rails 18 and 20 include flanges 28 which extend into certain of the guides 17. The channel rails 19 straddle the divisions 29 between the depressed channels or guides 17 and their adjacent flanges 30 constitute the guides 16 for the extension 125
125 guide flanges 23 of the sashes. It will be noted that the remote flanges of the remote channel rails 19 cooperate with the flanges 28 of the angle rails 18 and 20 to constitute the guides 16 for the upper outermost and the inner lowermost sashes 24 and 25. The 130

angle rails 18 and 20, the channel rails 19 and the plate 21 are fastened together as one body, that is, those at each side of the window, in any suitable manner, preferably by 5 means of spot-welding.

This structure consisting of the guides 16 and 17 may be moved into place by inserting them in a direction from the outside of the window, and when properly positioned, the 10 outer flanges 31 of the angle rails 20 are secured by spot-welding, as at 32, to the walls of the beads 33 of the stiles. The beads are continuations of the walls 15, as shown clearly in Figures 3 and 4. When the guides 16 15 and 17, consisting of the parts as above identified, are positioned, flanges 34 of the angle rails 18 are positioned as spaced from the flanges 14, there being U-shaped spacers 35 intervening the flanges 34 and 14 and which 20 are secured to said flanges in any suitable manner, preferably by spot-welding.

The spacing of the flanges 34 and 14 causes guides 36 to be formed for the reception and operation of the operating arms 37 which 25 are secured in any suitable manner, preferably by screws 38, to the weights 8. These arms extend transversely across the weights 10 in order to project through the guides 36. The U-shaped spacers 35 act as abutments 30 to limit the arms 37 in their movements, said arms projecting inwardly of the room in order to be easily grasped and facilitate the operation of the weights 8.

Mounted in the upper parts of the depressed channels or seats 7 are brackets or 35 holders 39 which are constructed from suitable sheet metal, consisting of the top walls 40 and the depending flanges 41 and 42 on three of the sides of the top 40. The top has 40 a cut-away portion or opening 43, and the parts which are cut to cause the openings to be formed are bent downwardly to provide depending supports 44. Secured in any suitable manner, preferably as shown at 45, to 45 the tops of the brackets or holders are plates 46 having depending supports 47 which are parallel with the depending flanges 41. The depending supports 44 are parallel with the depending flanges 42.

50 Journaled in bearings of the depending flanges 41 and the depending supports 47 are pulleys 48 for the sash chains 49 which are connected to the guide flanges 23 of the intermediate sashes 26 and 27, as shown in 55 Figure 12, and thereby counterbalance the two intermediate sashes. Journaled in bearings of the depending supports 44 and the end depending flanges 42 are pulleys 50 over which the sash chains 51 operatively ride. 60 These chains are connected, as at 52, to the guide flanges of the upper outermost and lower innermost sashes and, in turn, are connected at 53 to the weights 8 and 10, so that the weights 8 and 10 will counterbalance the 65 upper outermost and lower innermost sashes.

The brackets or holders 39 are secured in the depressed channels 7 in any suitable manner, preferably by spot-welding. The brackets or holders are above the chain guides and sash guides, so that the chains 70 will feed from the pulleys into the guides 17. It will be noted that the flanges 30 and the flanges 28 protrude into the guides 17 and act as abutment guides to prevent the sash 75 chains from jamming or buckling from their guides, as would otherwise be the case if the flanges 30 were omitted. The structure in the above identified application discloses guides for the sash chains but there are no means for preventing the sash chains from 80 buckling from the guides which receive the sashes. The present invention avoids such difficulty due to the depressed channels or guides 17 with the inwardly protruding flanges 30 which are spaced requisite to receive the guide flanges of the sashes. 85

As previously stated, the inner lowermost sash is weight balanced and is held locked, when lowered, by means of the latch 54 which engages the keeper 55 carried by the 90 sill 2 of the window. This latch and keeper are similar to those disclosed in the above identified application, and by such latching means, the lower sash may be maintained in a closed position with the weight 10 in a 95 raised position, as in dotted lines in Figure 2. The upper and lower intermediate sashes are counterbalanced by means of the chain 49 while the upper outermost sash is weightbalanced by means of the weights 8. 100

In order to hold the upper outermost sash locked in a closed position, when raised to its fullest extent, the lower portions of the weights have flanges 56 which may engage under the lateral flanges 12 of the guide 9. 105 In other words, the lower ends of the lateral flanges 12 are slightly cut away and when the upper outermost sash is raised to its full height, the weights 8 are lowered, and when in such position, the operator may pull outwardly upon the arms 37 and cause the flanges 56 of the weights 8 to engage under the lateral flanges 12. Due to the weights 8 being encased and the arms 37 extending inwardly of the room, there is no way of lowering the upper outermost sash from the exterior. 110

Each sash comprises the upper and lower and side rails 57, 58 and 59. The upper and lower rails of each of the sashes consist of 120 channel members 60, and secured, preferably by spot-welding, in the bottoms of the channels are angle strips 61, certain of the flanges of which are disposed parallel with the inner flanges of the upper and lower rails of the sashes and are spaced therefrom for the reception of the panes of glass 62, there being a suitable packing or filler, as at 63, preferably of asbestos or the like, thereby acting as 125 means to not only preclude the weather but 130

also to preclude metal contacting with such fragile material as glass and thereby preventing breaking of the panes. The channel members 60 are considerably thicker than the thickness of the panes of glass, hence the mounting of the angle strips 61.

The outer flanges of the upper and lower channel rails of the sashes constitute interengaging means between the sashes. In other words, by means of these flanges, the lower rail of the upper outermost sash and the upper rail of the upper intermediate sash are interlocked while the lower rail of the upper intermediate sash and the upper rail of the lower intermediate sash are interlocked. The upper rail of the lower innermost sash and the lower rail of the lower intermediate sash are interlocked due to the provision of such depending flanges. However, the upper rail of the upper outermost sash as well as the lower rail of the inner lowermost sash omit such flanges as those which constitute interlocking connections between the sashes. In fact, said rails are slightly thicker than the panes of glass in order to receive the packing or binding which precludes and prevents metal contacting with glass.

The side rails 59 of each sash are in the form of channels and are bent in cross sectional area to provide the extension guide flanges 23, the walls of which are spaced for the reception of the extensions 64 of certain of the flanges of the channel rails 60, as shown clearly in Figure 13. The angle strip 61 is first fastened in the channels of the side rails 59, so that the narrow flange thereof may overlie the ends of one of the sides of the side rails, then the channel rails 60 are positioned so that certain of their flanges will engage the inner faces of certain of the flanges of the channel rails 59 so that the extension 64 will engage in the space between the opposite sides of the extension guide flanges 23. The extensions 64 are secured in the spaces in any suitable manner, preferably by spot-welding, and in addition to this fastening means, rivets 52, such as in Figure 12, are employed. These rivets not only assist in holding the parts of the sash together but also constitute means to connect the sash chains to the sashes. The flanges which have the offset extensions 64 are slightly depressed for the reception of the sides of the channel rails 59, as shown at 65 in Figures 12 and 13. When the sash is completely constructed, these joints are finished and pressed into shape and the surfaces of the flanges of the top, bottom and side rails 60 are flush, thereby presenting a neat finish.

It is to be noted that this window frame or casement may be coupled to an adjacent window frame or casement, so as to provide a mullion between the two casements. To accomplish this result, it is the aim to em-

ploy substantially the same means as that disclosed in the heretofore identified application.

The invention having been set forth, what is claimed is:

1. In a window and sashes therefor, a casement comprising a lintel, a sill and stiles connecting the ends of the lintel and the sill, a plurality of sashes provided with guide flanges, sash chains connecting certain of the sashes and counterbalancing them, weights including sash chains connected to the other sashes, channel guides for the reception of the extension guide flanges of the sashes and receiving the sash chains, and means for insuring guiding the sashes and retaining the chains in the channel guides to prevent binding and buckling movement from the channel guides.

2. In a window and sashes therefor, a casement comprising a lintel, a sill and stiles connecting the ends of the lintel and the sill, a plurality of sashes provided with guide flanges, sash chains connecting certain of the sashes and counterbalancing them, weights including sash chains connected to the other sashes, channel guides for the reception of the extension guide flanges of the sashes and receiving the sash chains, means for insuring guiding the sashes and retaining the chains in the channel guides to prevent binding and buckling movement from the channel guides, and guides offset to the sides of the channel guides for the reception of the counterbalancing weights.

3. In a sheet metal window and balancing sheet metal sashes, a casement comprising a lintel, a sill and stiles connecting the ends of the lintel and the sill, sash and sash chain guides comprising channel plates, angular rails and channel rails constructed in sets, one set for each stile, the members of each set being fastened together in one body and placed in position adjacent the stile in a direction toward the interior of the window, and counterbalancing sashes mounted in the sash guides.

4. In a window and sashes therefor, a casement consisting of a lintel, a sill and stiles connecting the ends of the lintel and the sill, sash guides disposed in position next to the adjacent faces of the stiles and being arranged in such position from a direction toward the interior of the window, upper outermost and lower innermost and intermediate sashes mounted for movement in said guides, the intermediate sashes being counterbalanced, weights for counterbalancing the lower innermost and the upper outermost sashes, said weights being guided in the stiles and in perpendicular directions laterally of the sash guides, guides adjacent the stiles and the inner portion of the window, and arms connected to the weights which counterbalance the upper outermost

sashes and passing through the guides which are adjacent the stiles, whereby they may be grasped for operating said weights and resulting in lowering the upper outermost sash.

5. In a window and sashes therefor, a casement consisting of a lintel, a sill and stiles connecting the ends of the lintel and the sill, sash guides disposed in position next 10 to the adjacent faces of the stiles and being arranged in such position from a direction toward the interior of the window, upper outermost and lower innermost and intermediate sashes mounted for movement in 15 said guides, the intermediate sashes being counterbalanced, weights for counterbalancing the lower innermost and the upper outermost sashes, said weights being guided in the stiles and in perpendicular directions 20 laterally of the sash guides, guides adjacent the stiles and the inner portion of the window, arms connected to the weights which counterbalance the upper outermost sash and passing through the guides which are adjacent 25 the stiles, whereby they may be grasped for operating said weights and resulting in lowering the upper outermost sash, the guides for certain of the weights having certain of their walls cut away at their 30 lower portions, and means on certain of the weights to engage under said cut away walls to prevent movement of such weights.

6. In a sheet metal window structure, the combination with a sill, of opposed stiles 35 rising therefrom, a lintel connecting the upper ends of the stiles which are provided with depressed channels, sash weights guided in said channels, sash guides opposing the channels and adjacent thereto, upper 40 outermost and lower innermost and intermediate sashes engaging the sash guides, sash chains connecting the intermediate sashes whereby they counterbalance and being engaged in the sash guides for the intermediate sashes, sash chains engaging in 45 other of said sash guides and connected to the upper outermost and lower innermost sashes and in turn connected to said weights, sash pulleys over which said chains pass, and means extending within the sash guides and maintaining the chains against 50 buckling out of the sash guides.

7. In a sheet metal window structure, the combination with a sill, of opposed stiles 55 rising therefrom, a lintel connecting the upper ends of the stiles which are provided with depressed channels, sash weights guided in said channels, sash guides opposing the channels and adjacent thereto, upper 60 outermost and lower innermost and intermediate sashes engaging the sash guides, sash chains connecting the intermediate sashes whereby they counterbalance and being engaged in the sash guides for the intermediate sashes, sash chains engaging in 65

other of said sash guides and connected to the upper outermost and lower innermost sashes and in turn connected to said weights, sash pulleys over which said chains pass, means extending within the sash 70 guides and maintaining the chains against buckling out of the sash guides, the inner faces of the stiles having guides, arms connected to certain of the weights and engaging through the guides of the inner faces of the stiles, whereby certain of the weights may be manually actuated, thereby resulting in lowering the upper outermost sash.

8. In a sheet metal window structure, the combination with a sill, of opposed stiles rising therefrom, a lintel connecting the upper ends of the stiles which are provided with depressed channels, sash weights guided in said channels, sash guides opposing the channels and adjacent thereto, upper 80 outermost and lower innermost and intermediate sashes engaging the sash guides, sash chains connecting the intermediate sashes whereby they counterbalance and being engaged in the sash guides for the intermediate sashes, sash chains engaging in other of said sash guides and connected to the upper outermost and lower innermost sashes and in turn connected to said 85 weights, sash pulleys over which said chains pass, means extending within the sash guides and maintaining the chains against buckling out of the sash guides, the inner faces of the stiles having guides, arms connected to certain of the weights and engaging through the guides of the inner faces of the stiles, whereby certain of the weights may be manually actuated, thereby resulting in lowering the upper outermost sash.

9. In a sheet metal window frame structure, a sill, opposed stiles rising therefrom, a lintel connecting the upper ends of the stiles which are provided with depressed channels, said stiles also having depressed 100 combination sash and sash chain guides, counterbalancing and weight-balanced sashes cooperating with said guides and including chains operable in the guides, and means extending into the depressed sash guides for retaining the chains against buckling movement from their guides.

10. A sheet metal sash comprising upper, lower and side rails, the side rails consisting of channels provided with folded extension flanges, the upper and lower rails consisting of channels connected to the ends of the side rails and provided with extensions engaging between the sides of the folded extension flanges, means for secur- 115 120 125

ing the extensions of the upper and lower channels between the sides of the guide flanges, and means for mounting a pane of glass in the channels of the top, bottom and 5 side rails.

11. A sheet metal sash comprising upper, lower and side channel rails, means for connecting the ends of said rails together at the corners of the sash, and angle strips secured within the upper and lower channel rails and cooperating with certain of the channel rail flanges to provide means for the reception of the edges of a pane of glass, the perpendicular flanges of the angle strips being spaced from the other channel rail flanges, whereby said other channel rail flanges may interlock with similar flanges of adjacent sashes.

12. A sheet metal sash comprising upper, 20 lower and side channel rails, means for connecting the ends of said rails together at the corners of the sash, and angle strips secured within the upper and lower channel rails and cooperating with certain of their flanges to provide means for the reception of the edges of a pane of glass, the upper and lower channel rails being of substantial thickness and provided with extensions constituting interlocking flanges, the one of the 25 upper rail protruding outwardly and downwardly, the one of the lower rail protruding inwardly and upwardly.

13. In a sheet metal window frame structure, a sill, opposed stiles rising from the 30 sill, a lintel connecting the upper ends of the stiles which have depressed channels constituting guides for the reception of sash weights, said stiles having depressed sash guide channels, upper outermost, lower innermost and intermediate sashes having extensions engaging within the depressed sash guides, pulley boxings mounted in the first 35 named depressed channels of the stiles at their upper ends and including pulleys positioned over the sash guides, weights for the upper outermost and lower innermost sashes 40 and guided in the depressed channels of the stiles, a sash chain in certain of the depressed sash guides and connecting the intermediate sashes whereby they counterbalance and engaging over certain of said pulleys, sash 45 chains connecting the weights and the upper outermost and lower innermost sashes and operating in certain other of said depressed sash guides, means engaging within the depressed sash guides to retain the chains in 50 position and prevent them buckling from their guides, the inner faces of the stiles having guides, arms carried by the weights which counterbalance the upper outermost sash and projecting through the last named 55 guides inwardly of the room for actuating said weights, thereby resulting in lowering the upper outermost sash, and means for latching the weights which counterbalance the upper outermost sash to prevent the lowering of said sash.

14. In a sheet metal window frame structure, a sill, opposed stiles rising from the sill, a lintel connecting the upper ends of the stiles which have depressed channels constituting guides for the reception of sash 60 weights, said stiles having depressed sash guide channels, upper outermost, lower innermost and intermediate sashes having extensions engaging within the depressed sash guides, pulley boxings mounted in the first 65

named depressed channels of the stiles at their upper ends and including pulleys positioned over the sash guides, weights for the upper outermost and lower innermost sashes and guided in the depressed channels of the 70 stiles, a sash chain in certain of the depressed sash guides and connecting the intermediate sashes whereby they counterbalance and engaging over certain of said pulleys, sash chains connecting the weights and the upper 75 outermost and lower innermost sashes and operating in certain other of said depressed sash guides, and means engaging within the depressed sash guides to retain the chains in 80 position and prevent them buckling from their guides.

15. In a sheet metal window frame structure, a sill, opposed stiles rising from the sill, a lintel connecting the upper ends of the stiles which have depressed channels constituting guides for the reception of sash weights, said stiles having depressed sash guide channels, upper outermost, lower innermost and intermediate sashes having extensions engaging within the depressed sash 85 guides, pulley boxings mounted in the first named depressed channels of the stiles at their upper ends and including pulleys positioned over the sash guides, weights for the upper outermost and lower innermost sashes 90 and guided in the depressed channels of the stiles, a sash chain in certain of the depressed sash guides and connecting the intermediate sashes whereby they counterbalance and engaging over certain of said pulleys, sash 95 chains connecting the weights and the upper outermost and lower innermost sashes and operating in certain other of said depressed sash guides, means engaging within the depressed sash guides to retain the chains in 100 position and prevent them buckling from their guides, the inner faces of the stiles having guides, arms carried by the weights which counterbalance the upper outermost sash and projecting through the last named 105 guides inwardly of the room for actuating said weights, thereby resulting in lowering the upper outermost sash, and means for latching the weights which counterbalance the upper outermost sash to prevent the lowering of said sash.

16. In a sheet metal window frame structure, the combination with stiles provided with guides for the reception of a plurality of sashes, of a sill on which the stiles are supported, a main lintel connecting the upper ends of the stiles and provided with an upwardly formed depression extending longitudinally with the lintel, whereby a housing for pulley boxings may be formed.

17. In a sheet metal window structure, the combination with a window sill, of opposed stiles rising from the sill, a main lintel connecting the upper ends of the stiles and provided with an upwardly formed depre-

- sion extending the length of the lintel, pulley boxings secured in the ends of the depression, said pulley boxings comprising opposed plates, spacing and journal pins 5 connecting said plates, pulleys mounted on the journal pins, said pins constituting means to hold the plates rigidly spaced thereby preventing binding of the ends of the pulleys on the plates.
- 10 18. In a window structure, a frame, sash and weight guides carried by the stiles of said frame, a lintel frame connecting the upper ends of the stiles, pulley boxings countersunk in the lintel and provided with 15 pulleys adjacent to and coinciding with the guides, upper outermost and lower innermost sashes mounted in certain of the sash guides, upper and lower intermediate sashes mounted in other of said sash guides, means 20 passing over certain of the pulleys and connecting the intermediate sashes, a balancing weight mounted in one of said weight guides, means passing over another of the pulleys and connecting said weight and the 25 lower innermost sash, second weights mounted in the other weight guides, and means passing over others of said pulleys and connecting the second weights and the upper outermost sash.
- 30 19. In a window structure, a frame, sash and weight guides carried by the stiles of said frame, a lintel frame connecting the upper ends of the stiles, pulley boxings countersunk in the lintel and provided with pul- 35 leys adjacent to and coinciding with the guides, upper outermost and lower innermost sashes mounted in certain of the sash guides, upper and lower intermediate
- sashes mounted in other of said sash guides, means passing over certain of the pulleys 40 and connecting the intermediate sashes, a balancing weight mounted in one of said weight guides, means passing over another of the pulleys and connecting said weight and the lower innermost sash, a second 45 weight mounted in the other weight guide, means passing over others of said pulleys and connecting the second weight and the upper outermost sash, and means carried by the second weights and cooperating between 50 the weight guides and engageable with the lower extremity of one of the weight guides to retain the second weights against movement and lock the upper outermost sash.
- 55 20. In a window structure, a frame hav- ing weight guides, a plurality of sashes mounted in said frame for vertical move- 60 ments, means operatively connecting certain of said sashes, whereby they may counter- balance each other, weights operable in cer- tain of the weight guides and operatively connected to another of said sashes, second 65 weights mounted in other of said weight guides and operatively connected to other of said sashes, said weight guides having op- posed weight spacing tongues to retain the weights separated during their vertical movements, and means carried by the second weights for engagement with the lower ex- 70 tremities of certain of the spacing tongues to latch the second weights for locking the sash which operatively connects with said second weights.

In witness whereof the inventor's signature is hereunto affixed.

GEORGE W. LANCASTER.
